UNITED STATES PATENT OFFICE.

HIRAM PERCY MAXIM, OF HARTFORD, CONNECTICUT, ASSIGNOR TO MAXIM SILENT FIREARMS COMPANY, OF NEW YORK, N. Y., A CORPORATION OF NEW JERSEY.

SAND-BOX FOR RIFLE PRACTICE.

941,642.

Specification of Letters Patent. Patented Nov. 30, 1909.

Application filed January 7, 1909. Serial No. 471,085.

To all whom it may concern:

Be it known that I, HIRAM PERCY MAXIM, a citizen of the United States, residing in the city of Hartford, in the State of Connecticut, have invented certain new and useful Improvements in Sand-Boxes for Rifle Practice, of which the following is a specification, reference being had to the accompanying drawing, forming a part 10 hereof.

This invention has for its object to produce an improved sand box into which bullets may be discharged in rifle practice, the purpose being to produce a sand box of this 15 character which shall be easily portable, if desired, and can be used indoors as well as outdoors, provision being made whereby the escape of sand through bullet holes is prevented.

20 In accordance with the invention, provision is made whereby the mass of fibrous material is supported in front of the body of sand in which the momentum of the bullets is mainly taken up, the fibrous material 25 preventing the flow of sand through the holes made by the bullets through the inclosing wall.

The invention will be more fully explained hereinafter with reference to the accompanying drawing in which it is illustrated 30 and in which—

Figure 1 is a view in perspective of a sand box which embodies the invention together with supports for the same. Fig. 2 is a 35 view of the sand box, on a larger scale, in longitudinal vertical section. Fig. 3 is a view thereof in horizontal section on the plane indicated by the broken line 3—3 of Fig. 2, looking in the direction of the 40 arrows.

As shown in the drawing, the device comprises a box or casing *a*, which may be of any suitable material, preferably of wood for the sake of lightness, and of any convenient shape. The box or casing may have 45 an open top and may be provided with a cover *b* which, for convenience, may be hinged to the body of the box. The box or casing is mainly adapted to receive a body *c* of sand or other similar material, in which, as is well understood, the momentum of bullets is quickly absorbed, and in front of the same, either within or outside 50 of the box *a*, is supported a body *d*, such as waste for example, through which the

bullets pass into the body of sand, the waste acting to prevent the flow of sand through the holes made by bullets through the inclosing wall, whether such wall be between the fibrous material and the sand or outside 60 of the fibrous material. In the box shown in the drawing the fibrous material is placed within the body of the box, a partition *e*, being mounted in guides *f* to retain the sand in the larger compartment formed thereby, 65 at least while the fibrous material is being packed in the smaller compartment. Obviously, the partition *e* may be withdrawn after the two compartments are filled, but it is preferably allowed to remain in position between the sand and the fibrous material. 70

If the partition be made of wood, as is most convenient, it may have an opening *g* 75 therein sufficiently large to receive the bullets which are directed with ordinary accuracy, this opening being covered by a renewable piece of material, such as canvas, so that when it is cut to pieces by the bullets it may be removed, the partition being withdrawn, and replaced by another cover, being held in position by any suitable means, as by glue. The front *a'* of the box is also provided with a similar opening *a''* so that the front shall not be too quickly destroyed by 80 the bullets and this opening *a''* is also provided with a renewable cover *i*, which, for convenience in renewing, may be carried by a false front *k* which is also provided with an opening *k'*. The false front *k* is removable, being supported, if desired, by guides *l*, although obviously it would be sufficiently held in place by the mass of fibrous material. The bottom of the box may be extended, as at *a''*, and provided with a rim or 90 flange *a'''*, forming a lip to receive such sand as may eventually find its way through the waste and thereby prevent it from being scattered upon the floor. 95

In the embodiment of the invention shown 100 in the drawings the box is provided with handles *m* by which it may be readily transported and it is also provided with legs *n*, *o*, to support the box at a proper height. The legs *n* and *o* are hinged to the bottom 105 of the box, as at *p* and the inside legs *n* are slotted, as at *n'*, to permit relative movement of a rod *q* which is secured at its ends in the outer legs *o*, so that the legs may be folded up against the bottom of the box and 110

at the same time be braced laterally when they are extended. To prevent the legs from folding up against the bottom of the box the lower ends thereof are stepped in 5 slotted feet r , the slots r' therein preventing the spreading of the legs longitudinally when the box is elevated.

It will be evident that various changes in the details of construction may be made to 10 suit convenience without departing from the spirit of the invention.

If a target is desired, other than the front of the box, such target, as represented at s , may be conveniently hung in front of the 15 box as by spring clips t engaging the extended front wall of the box, or in any other convenient manner.

I claim as my invention:

1. A sand box for rifle target practice, 20 comprising a box or casing, a partition therein forming a compartment for sand and another compartment in front thereof and a mass of fibrous material disposed in the forward compartment.
- 25 2. A sand box for rifle target practice, comprising a box or casing and a partition dividing the same into compartments for the reception of sand and fibrous material respectively.
- 30 3. A sand box for rifle target practice, comprising a box or casing forming a re-

ceptacle for sand and having an opening in its front wall, a cover for said opening and a mass of fibrous material interposed between the sand and the front wall.

4. A sand box for rifle target practice, comprising a box or casing and a removable partition dividing the box or casing into compartments for sand and fibrous material respectively, said partition having an opening and a cover therefor. 40

5. A sand box for rifle target practice, comprising a box or casing forming a receptacle for sand and a mass of fibrous material interposed between the sand and the front of the box or casing, the box or casing having a lip projecting from its lower front end for the reception of such sand as may work through the fibrous material. 45

6. A sand box for rifle target practice, comprising a box or casing forming a receptacle for sand, folding legs secured to the bottom of the box or casing and feet adapted to engage the lower ends of such folding legs and maintain them in extended position. 50

This specification signed and witnessed this 5th day of January, A. D., 1909.

HIRAM PERCY MAXIM.
